BEDSIDE TRAY-TABLE SUPPORT

Jesse L. Whitaker, Great Falls, Mont.

Application June 15, 1951, Serial No. 231,845

5 Claims. (Cl. 128—375)

1

This invention relates generally to therapeutic apparatus and is directed particularly to an improved support structure designed for bedside use by sick persons, although it may be used in other capacities.

A particular object of the present invention is to provide a novel stand or support structure by means of which a convenient means is provided for supporting a tray or other object adjacent to or over a sick bed either for the purpose of providing the occupant of the bed with means for supporting a magazine, book, foodtray or the like or for supporting a therapeutic instrument such as a heat cradle or the like.

Another object of the invention is to provide a supporting structure of the character stated having a novel base unit by means of which it may be readily attached to the side frame of a bed and rigidly secured in position thereon.

Still another object of the invention is to provide a supporting structure of the character stated having a top structure which may be turned in a horizontal plane to any desired position and which may also be raised or lowered on a horizontal pivotal axis or may be raised or lowered upon a vertical supporting standard thus providing means for placing the top structure of the support in any one of a number of positions for use.

A still further object of the invention is to provide in a device of the above described character a novel means for coupling together a tray and a heat unit designed for physical therapy, the tray portion of the structure being a permanent part of the top part of the support with the heat treating unit detachably connected therewith.

Other objects and advantages of the invention will become apparent as the description of the same proceeds and the invention will be best understood from a consideration of the following detailed description taken in connection with the accompanying drawings forming a part of the specification, with the understanding, however, that the invention is not to be limited to the exact details of construction shown and described since obvious modifications will occur to a person skilled in the art.

In the drawings:

Figure 1 is a view in side elevation of a support structure constructed in accordance with the present invention and showing the same mounted upon a bed rail and further showing the table tray in dotted outline in a tilted position.

Figure 2 is a view in elevation of the device looking at the outer side thereof.

2

Figure 3 is a horizontal section taken substantially on the line 3—3 of Figure 1.

Figure 4 is a horizontal section taken substantially on the line 4—4 of Figure 1, looking upwardly in the direction indicated by the arrows.

Figure 5 is a view in side elevation of the base portion of the structure showing the manner of using the same as a pedestal to rest on the floor.

10 Figure 6 is a view in side elevation of the top portion of the structure showing in side elevation thereon a heat oven.

Figure 7 is a view in perspective of the heat oven looking toward the open front end thereof.

15 Figure 8 is a view in perspective of the back end portion of the heat oven.

Figure 9 is a vertical transverse section taken substantially on the line 9—9 of Figure 6.

Figure 10 is a view in top plane of the heat oven showing the cover opened to show the heating elements therein.

20 Figure 11 is a view in perspective of one end portion of the table tray showing the grooved side flanges.

25 Figure 12 is a view in perspective of a clamp element.

Referring now more particularly to the drawings the numeral 10 generally designates a portion of an angle beam representing a side rail of a bed structure, upon which the present supporting device is designed to be secured. The device may, however, be stood upon any flat surface such as the floor or the like as will be hereinafter set forth.

30 In the preferred embodiment of the present invention as here illustrated there is provided a base unit which is generally designated 12 and which is here shown as being in the form of a frame having the side rail or bar 14 which is preferably of angle iron material, from each end of which extends one of two parallel arms 16. As shown the arms 16 extend from the same side of the side rail 14 and they are connected intermediate their ends by the bar 18 which is parallel with the rail 14.

35 Each of the arms 16 terminates in the underturned hook forming portion 20 which is designed to receive the inner edge of the horizontal flange portion of the bed rail 10 with the arm lying across the top of such flange whereby the unit 12 is disposed horizontally, and extending outwardly, from and with respect to the bed rail.

40 In order to secure the unit 12 to the bed rail when the hooked ends 20 of the arms are engaged therewith as described, each arm has slidably supported thereon a clamp element 22 which

45 50 55

is moved up against the outer side of the bed rail and secured to the arm against movement thereon so that the hook end of the arm cannot be disengaged from the bed rail.

The clamp elements each comprises a short length of substantially U-shaped material having the bottom portion 23 and the opposite upstanding flange portions 24 through each of which is formed a slot 25. An arm 16 extends through the two slots across the bottom portion 23 of the clamp and there is threaded through a tapped opening 26 in the bottom portion 23, a binding screw 27 which is threaded upwardly into tight contact with the arm so as to hold the clamp against movement on the arm.

Secured to the outer side of the base rail 14 is a vertical guide 28. This guide has threaded through the side thereof the set screw 29 for the purpose about to be described.

At the ends of the base 12, each arm 16 carries a brace rod 30 and these brace rods are in outwardly directed convergent relation and are secured to and support at their outer ends, an upper guide 31 which is in vertical alignment with the guide 28.

The numeral 32 designates a vertical post or standard which extends at its lower end through the aligned guides 28 and 31 and is secured in adjusted position by the set screw 29.

Removably supported upon the upper end of the post 32 is the top unit which is generally designated 33. This top unit also includes a tray unit which is generally designated 34 and while it is removably secured to the top unit and may be considered as an integral part thereof it may be removed if desired although it normally remains as a fixed part of the top unit.

The unit 33 comprises a horizontal bar 35 which has secured thereto and upon one side thereof midway between its ends, a socket 36 which, in the set up structure, is downwardly directed. Disposed in spaced parallel relation with the bar 35 and below the same, is an angle bar 37, one flange of which is vertically disposed as shown and this angle bar is connected with the top bar 35 by the vertical legs 38.

Secured vertically to the outer side of the vertical flange portion of the angle bar 37, is a guide sleeve 39.

The upper end of the post 32 extends through the guide sleeve and is positioned at its top in the socket 36 so that the entire unit 33 with the tray 34 is supported on the post 32 for free rotation in a horizontal plane and may be easily and quickly lifted from the post if desired.

On the side of the top bar 35 opposite from the socket 36, is a rectangular frame consisting of the spaced parallel inner and outer members 40 and 41 respectively and the connecting side members 42, the latter being formed of angle iron material preferably as shown.

The inner member 40 of the top unit frame is connected by hinges 43 with the bar 35 so that the frame may swing vertically.

For the bracing of the frame of the top unit in a set position, there are provided the two brace arms 44, each of which is pivotally attached as at 45 to a side member 42 of the frame and extends downwardly and across the top edge of the vertical flange portion of the angle bar 37. Each of the arms 44 is provided with a number of notches 46 for engagement with the flange of the angle bar 37 to support the top unit frame in adjusted position.

To add to the strength and rigidity of the struc-

ture and also to provide a convenient means for grasping the arms 44 to disengage them from the angle bar 37 or engage them as desired, the inner and lower ends of the arms 44 are connected by the yoke bar 47.

The tray 34 overlies the bar 35 and rests upon the frame which is hingedly attached to the bar and is secured thereto by the screws 48. This tray comprises a bottom portion 49 and the upstanding side flanges 50 and end flanges 51 as shown. This tray may be of any suitable form or shape but it is preferred that it be of elongated rectangular design and about twice as long as it is wide and is set upon the top unit frame so that the long sides 50 will be parallel with the side members 42 of the frame on which it is resting.

The major portion of the length of the tray or table 34 extends beyond the outer member 41 of the top unit frame which is the side thereof remote from the bar 35 and since the supporting structure when set up upon a bed rail has the bar 35 toward the outside or away from the bed it will be seen that the tray or table projects inwardly a substantial distance over the bed beyond the top unit 33. Thus by manipulating the brace arms 44 the top unit frame can be tilted so that the table or tray can be placed at an elevation thus making it convenient for the occupant of the bed over which the tray is placed, to position a book, magazine or the like at a convenient angle for reading.

Designed for use upon the support and for attachment to the tray or table is an electric heating unit or oven which is generally designated 52. This oven comprises an elongated body having the side walls 53 which are connected together at one end by the end wall 54 while the opposite end of the body is open and the body is also open throughout its length in the bottom thereof. There is thus provided an elongate oven like structure which is open at one end and throughout the bottom. The top of the heating structure comprises a domed hood 55 which is hinged along one side as indicated at 56 to one side wall while at the opposite side suitable fasteners 57 are provided to secure the top in position on the side walls of the structure. Within the domed top 55 of the heating device are housed suitable electric heating units 58, the electric current flow to such units being controlled by a suitable switch 59 mounted on one side wall 53.

The side walls 53 carry upon their inner faces and adjacent to the bottom edges thereof the longitudinally extending flanges 60 and the distance between the lower edges of the walls 53 is substantially the same as the overall width of the tray or table 34 so that the heating unit or oven may be placed directly over and rested upon the tray 34 and in order to maintain the unit in coupled relation with the tray or table, the side flanges 60 of the tray are provided with the longitudinally extending slots 61 which slidably receive the flanges 60 of the heating unit or oven. Thus in placing the heating unit in position it is slid onto the tray or table from one end of the latter, the flanges 60 being guided into the slots 61. The heating unit or oven 52 would be positioned on the tray or table with the wall end 54 away from the bed so that a person lying in the bed could place his arm or leg in the oven conveniently and comfortably to receive treatment from the heat generated by the heating units 58.

It will be readily seen that the support of the present invention when mounted upon a bed rail

in the manner described, can be raised or lowered as desired by loosening the binding screw 29 so as to permit the post to slide through the guides 28 and 31. If it is more convenient to use the support on the floor this may be done by extending the lower end of the post 32 a short distance below the bottom rail 14 of the base unit 12 so as to function as a third leg in conjunction with the clamp screws 27, the heads of which would rest upon the floor surface.

From the foregoing it will be readily seen that there is provided in the present invention a novel and very desirable device for use particularly in connection with a sick bed or for a person desiring heat therapy, whereby the patient will be able to enjoy many conveniences which are at the present time not easily available with stands or tables of the type at present in use.

It will also be apparent that the support structure when secured to the frame of a bed, will be rigidly located so that it cannot be accidentally shifted or tipped over as is the case with bedside tables or trays which are intended to be stood directly upon the surface of the bed.

By means of the socket 36 and guide 39, the base frame and post can be allowed to remain in position and the top unit can be easily and quickly removed if and when necessary or replaced without difficulty so as to be instantly ready for use and the top unit can also be swung around to an out of the way position if it is not desired to completely remove it from the supporting post or standard 32.

I claim:

1. A support structure of the character set forth comprising a base, a pair of vertically spaced guides carried thereby, a post slidably engaged in said guides, means for securing the post in a guide, a top unit including a rigid member, means for mounting said rigid member on the top end of said post, a flat body providing a tray table, means pivotally coupling said body to the rigid member for swinging from a horizontal position to a tilted position, and means for adjustably holding the body in one of said positions, said rigid member comprising a bar, the said means pivotally coupling the flat body to the rigid member including a frame having one side adjacent to and parallel with the bar and hinges coupling the said side of the frame to the bar, and the said means for adjustably holding the flat body in one of the said positions comprising a second bar below and parallel with the rigid member, a pair of arms each pivoted at one end to a side of said frame and extending across said second bar, a connecting member between the other ends of said arms and means for adjustably coupling the arms with said second bar.

2. A support structure of the character set forth comprising a base, a pair of vertically spaced guides carried thereby, a post slidably engaged in said guides, means for securing the post in a guide, a top unit including a rigid member, means for mounting said rigid member on the top end of said post, a flat body providing a tray table, means pivotally coupling said body to the rigid member for swinging from a horizontal position to a tilted position, and means for adjustably holding the body in one of said positions, said base being in the form of a rectangular unit 70

and including two arms forming two opposite sides of the base and each having a hook at one end for engagement with a supporting body, and a clamp on each arm for coaction with the hook thereon in securing the hook to said supporting body, the hook ends of the arms being at one of the other two opposite sides of the base and said guides being adjacent to the other one of the said other two opposite sides of the base from the hooks.

3. A device of the character set forth comprising, in combination, a base unit, a post supported for vertical adjustment thereon, a top unit comprising a frame, a member supported on the top of said post, a hinge coupling between the frame and member by which the frame may swing vertically, a tray-table secured to the frame, and a limb treating heat oven removably secured on said tray-table, the means for securing the oven to the tray table comprising grooves in and longitudinally of two opposite sides of the tray table, and ribs extending longitudinally of the inner sides of two side walls of the oven at the bottom edges of such walls for sliding engagement in said grooves.

4. A bedside fixture adapted for support either on a bed rail or on the floor to maintain an article in position relative to the bed; said fixture comprising a substantially rectangular base unit 30 including two spaced substantially parallel arms, a hook carried at one end of each arm for engaging a flange of a bed rail when the arm is disposed thereacross, a bar connecting the other ends of the arms together, a pair of aligned vertically spaced guides carried by the unit, the lower guide being secured to said bar, a clamp element supported on each arm for movement relative to the adjacent hook to engage a side of the bed rail and secure the hook to the bed rail, a post adjustably engaged through said guides, means carried by a guide to secure the post against movement therein, and means carried by each clamp for and projecting downwardly from the underside of the base unit to function as a foot to rest upon a floor in coaction with the bottom end of the post when the unit is detached from the bed rail.

5. The invention as set forth in claim 4, wherein in the said clamp element comprises a substantially U-shaped member having upstanding slotted legs through which an arm extends and a binding screw threaded upwardly through said member between the legs for engagement with the overlying arm, said binding screw constituting the last named means which functions as a floor engaging foot.

JESSE L. WHITAKER.
